[57] CLAIM

The ornamental design for a sheet former folder, as shown and described.

DESCRIPTION

FIG. 1 is a perspective view of a sheet former folder showing my new design;

FIG. 2 is a front elevational view thereof;

FIG. 3 is a rear elevational view thereof;

FIG. 4 is a left side elevational view thereof, the right side being a mirror image of the left side shown;

FIG. 5 is a bottom plan view thereof;

FIG. 6 is a top plan view thereof; and

FIG. 7 is another perspective view thereof.

The broken line representation of rollers and continuous sheet material in FIG. 7 is for illustrative purposes only and forms no part of the claimed design.

FIG. 1.

FIG. 7.

FIG. 2.

FIG. 3.

FIG. 4.

FIG. 5.

FIG. 6.
